US00D822838S

(12) **United States Design Patent** (10) Patent No.: **US D822,838 S**
(45) Date of Patent: **** Jul. 10, 2018**

(54) **ELECTRODE ARRAY**

- (71) Applicant: **Medasense Biometrics Ltd.**, Ramat Gan (IL)
- (72) Inventors: **Galit Zuckerman-Stark**, Tel Aviv (IL); **Adi Costa**, Kfar Saba (IL); **Shimon Hayun**, Rosh Haayin (IL); **Refael Gil Koby**, Kochav Yair (IL); **Naum Muchnik**, Yokneam-Ilit (IL); **Avi Kayton**, Tel Aviv (IL)
- (73) Assignee: **MEDASENSE BIOMETRICS LTD.**, Ramat Gan (IL)
- (**) Term: **15 Years**
- (21) Appl. No.: **29/581,729**
- (22) Filed: **Oct. 21, 2016**

CLAIM

The ornamental design for an electrode array, as shown and described.

DESCRIPTION

FIG. 1 is a top perspective view of an electrode array in accordance with the new design;

FIG. 2 is a bottom perspective view of the electrode array;

FIG. 3 is a back view of the electrode array;

FIG. 4 is a right side view of the electrode array;

FIG. 5 is a front view of the electrode array;

FIG. 6 is a left side view of the electrode array;

FIG. 7 is a top view of the electrode array; and,

FIG. 8 is a bottom view of the electrode array.

1 Claim, 8 Drawing Sheets
